UNITED STATES PATENT OFFICE.

CARL WEGESCHEIDT, OF COLOGNE-BAYENTHAL, GERMANY.

GAS-PURIFIER

964,719.

Specification of Letters Patent. Patented July 19, 1910.

Application filed January 28, 1910. Serial No. 540,578.

To all whom it may concern:

Be it known that I, CARL WEGESCHEIDT, engineer, a citizen of the German Empire, residing at 60 Goltsteinstrasse, Cologne-Bayenthal, Germany, have invented certain new and useful Improvements in or Relating to Gas-Purifiers, of which the following is a specification.

This invention relates to a gas purifier and has for its object to utilize in the most favorable manner possible the space of the purifier, and to obtain the best possible purification and to manufacture purifiers having a very large output.

According to this invention, the above objects are attained by providing the purifier with gas-conduits or flues which are distributed throughout the whole volume of the purifier and some of which are used for introducing the gas to and the others for discharging it from the purifier. Owing to this arrangement, the thickness of the layers of purifying material through which the gas to be purified has to pass, can be varied. At the same time it is possible to make purifiers of any desired output, as the gas to be purified has merely to travel from its supply pipe to the discharge pipes which are adjoining it, so that apparatus of any desired height may be built.

A simple construction easy to attend, is obtained by branching off the different gas supply conduits from a single chamber and also making the mouth pieces of the outlet conduits to open into a single collecting chamber.

In order to insure uniformity of action in the various portions of the apparatus with such an arrangement of a number of gas conduits, the coöperation of which in one and the same apparatus corresponds to a number of purifiers arranged side by side, it is advisable to provide the different gas supply conduits with indicator devices which indicate the gas flow in the conduits. This can be effected in a simple manner by arranging in the conduits, adjustable throttle valves and connecting them to indicating devices operated by the pressure in front of, and behind, the throttle valves. As the quantity of gas passing through the conduit for a given size of cross-section passage area left free by the throttle valve, depends on the difference in the pressures in front of, and behind, the throttle valves, it is in that

way possible to control accurately the working of the apparatus in all its parts.

It is advisable to make the gas pipes in the apparatus of louver-like members arranged in a roof-like formation, the roof surfaces of which are perforated in such manner that on the one hand they are used as supports for the purifying mass, while on the other hand they allow the gas to pass. The louvers can be arranged in an adjustable manner so that, by a suitable movement of the same, support can be withdrawn from the purifying mass when it is desired to discharge it from the apparatus.

A purifying apparatus constructed in accordance with the above principles, is illustrated by way of example in the accompanying drawing.

Figure 1 is a vertical section through the purifier, in the direction transversely of the gas conduits. Fig. 2 is a portion of the purifier, partly in section and partly in side elevation, in the direction parallel to the gas conduits, and Fig. 3 is a diagrammatic view of the regulating and indicator device for different pipes, branching off from a single supply.

The purifier chamber is surrounded on all sides with walls. The two front walls which are at a right angle to the gas conduits arranged in the purifier, are formed into double walls. The purifier walls at the gas inlet side, are marked 1, 2, while the walls at the outlet side, are marked 3, 4. The walls 2, 4, form supports for a number of girders 5 which, in their turn, support the louvers. The louvers pass through the purifier chamber from one wall to the other and are distributed as uniformly as possible in the said space. The louvers which afford support to the purifying mass, form canal-like hollow spaces in the interior of the purification mass, which hollow spaces form flues for the gas. The louvers are divided into two groups, one group 6 forming with the supporting plates 7 the supply conduit for the gas, and the other group 8 forming with the support plates 9 outlet conduits for the gas. The louvers are pivoted at their upper ends to projections of the girders 5, while the bottom ends are pivoted by links 10 or 11 to longitudinally adjustable rods 12 or 13 mounted vertically in the purifier. The rods 12 and 13 are connected at the upper end by strong girders as shown for

the rods 12 on the drawing at 14. The girders 14 as well as the girders corresponding to the rods 13, are held in the raised position by a supporting device consisting of cams 15 rotatably mounted on the girders 14, in connection with the abutments 16 secured to the apparatus. The rotatable cams 15 are provided with eyes 17, 18 in order to release at will the rods 12 or 13 in their raised position, so as to enable them to fall down into the lower position, or so as to secure them in their raised position.

The lower end of the apparatus is provided with conical outlet branches 19 for the purifying mass, which are held closed by means of lids 20 with closing brackets 21.

In the construction of the purifier illustrated in the drawing, it has been assumed that there is a cellar or pit under the chamber of the purifier, so that transport trucks can be brought in the cellar or pit under the openings of the outlet hoppers 19, for the purpose of receiving the purified mass. For filling the trucks traveling hoppers 25 could be advantageously used, with an oscillating bottom closing device, such as indicated in Fig. 1 of the drawing at 22. Gas is admitted into the intermediate space between the walls 1 and 2. From the said space, openings 23 lead to the hollow spaces under the louvers 6. Throttle valves 24 are used for closing the openings 23 to a greater or smaller extent. The gas outlets leading from the hollow spaces under the louvers 8, to the intermediate space between the walls 3, 4, are marked 25.

The working of the purifying device is as follows:—Before the purifier is started, it is filled with the purifying mass, which can be effected from a floor situated above the purifier. The purifier is filled with the mass in such manner that under each of the louvers 6, 7 is left a conduit-shaped hollow space, the shape of which on the lower surface is determined by the angle of slope of the material. After the apparatus has been filled, gas is admitted into the space between the walls 1, 2. The gas passing through the openings 23 in the wall 2, spreads among the various conduits closed by the louvers 6. By suitably adjusting or setting the slide valves 24, the admission of gas to the conduits corresponding to the louvers 6, can be regulated. From the inlet conduits arranged under the louvers 6, the gas passes through the intermediate spaces between the supporting surfaces 7, into the purifying mass, and penetrates through the layer of the mass situated between the supply conduit, and the outlet conduits arranged all around and closed by the louvers 8. The arrows in Fig. 1 of the drawing indicate the path of the gas. From the outlet conduits situated under the louvers 8, the purified gas passes through the openings 25 in

the wall 4, into the space between the walls 4 and 3, and is carried away from that point. The layer of the purifying mass, through which the gas is to pass, can be made any desired thickness. A thickness of 70 layer of about 600 mm. has been found by the applicant to be very suitable.

When it is desired to empty the purifier, the rods 12, 13 are moved from their raised position into the lower position, which, as regards the rods 12, is effected, according to the drawing, by raising the eyes 17 and subsequent lowering of the rods. The rotatable supporting plates 15 then slide away from the abutments 16, so that the system of 80 rods 12 can sink, the louvers assuming a position such as that shown in the drawing for a group of louvers 6. Owing to such a rotation or turning of the louvers, all support is withdrawn from the purifying mass, 85 so that when the closing devices 21 are opened, the purifying mass is freely discharged through the outlet cones 19.

Fig. 3 shows a device for a more accurate control of the flow in the various gas supply 90 conduits. It will be seen here, as in Fig. 2, that there are provided adjustable throttling valves 26^a, 16^b, 26^c mounted in the supply conduits 27^a, 27^b, 27^c arranged side by side. Branch conduits 28^a, 29^b lead from the pipes 95 27^a in front of, and behind, the throttling valves 26^a, to a differential-pressure gage device 30^a. The differential pressure gage indicates in a well known manner, the currents in the pipe sections 27^a. Calculation 100 shows that if the cross-sectional area of passage left free by the throttle valve, be indicated by F, the quantity of gas passing through the pipe by V, the difference of pressures in front of, and behind, the 105 throttle valve by h and a constant by C, then $V = C G h$. If F is fixed as a function of h in a table for a given V, it is possible, without difficulty and special training, to adjust the passage of gas, in accordance 110 with the indications of the pressure measuring devices, to the desired extent. Such a regulating device as shown in Fig. 3, can be easily fitted to practical purifier constructions.

What I claim is:

1. In a gas purifying device the combination of gas channels formed by movable louvers arranged in a roof-like manner one above the other for introducing the gas to be purified into the purifier, means for supplying gas to the louvers, similarly arranged movable louvers for carrying away the purified gas from the purifier, and means for controlling the position of the louvers. 120

2. In a gas purifying device the combination of gas channels formed by movable louvers arranged in a roof-like manner one above the other for introducing the gas to be purified into the purifier, means for sup- 130

- plying gas to the louvers, similarly arranged movable louvers forming channels to carry away the purified gas from the purifier, adjustable rods mounted vertically in the purifier, pivotal connections between the louvers and said adjustable rods, and means for supporting the rods in their adjusted positions.
3. In a gas purifying device the combination of gas channels formed by movable louvers arranged in a roof-like manner one above the other for introducing the gas to be purified into the purifier, means for supplying gas to the louvers, similarly arranged movable louvers forming channels to carry away the purified gas from the purifier, girders located over each channel, and means for supporting the louvers from the girders.
4. In a gas purifying device the combination of gas channels formed by movable louvers arranged in a roof-like manner one above the other for introducing the gas to be purified into the purifier, means for supplying gas to the louvers, similarly arranged movable louvers forming channels to carry away the purified gas from the purifier, girders located over each channel for supporting the louvers, and pivotal connections between the girders and louvers.
5. In a gas purifying device the combination of gas channels formed by movable louvers arranged in a roof-like manner one above the other for introducing the gas to be purified into the purifier, means for supplying gas to the louvers, similarly arranged movable louvers forming channels to carry away the purified gas from the purifier, girders located over each channel for supporting the louvers; pivotal connections between the girders and louvers, and rods pivotally connected to the louvers.
6. In a gas purifying device the combination of gas channels formed by movable louvers arranged in a roof-like manner one above the other for introducing the gas to be purified into the purifier, means for supplying gas to the louvers, similarly arranged movable louvers forming channels to carry away the purified gas from the purifier, girders located over each channel for supporting the louvers, pivotal connections between the girders and louvers, rods pivotally connected to the louvers, and means for maintaining the rods and louvers in the raised position.
- 55 7. In a gas purifying device the combination of gas channels formed by movable louvers arranged in a roof-like manner one above the other for introducing the gas to be purified into the purifier, means for supplying gas to the louvers, similarly arranged movable louvers forming channels to carry away the purified gas from the purifier, girders located over each channel for supporting the louvers, pivotal connections between the girders and louvers, rods pivotally connected to the louvers for moving them, and means including rotatable cams and abutments for sustaining the rods and louvers in the raised position.
8. In a gas purifying device the combination of gas channels formed by roof-like louvers arranged one above the other for introducing the gas to be purified into the purifier, means for supplying gas to the louvers, similar louvers forming channels to carry away the purified gas from the purifier, girders for supporting said louvers, adjustable rods mounted vertically in the purifier, and pivotal connections between the louvers and said adjustable rods.
9. In a gas purifying device the combination of gas channels distributed throughout the whole of the purifying mass, alternating in vertical rows with each other, and formed by movable roof-like louvers arranged one above the other for introducing the gas to be purified into the purifier, similar movable louvers forming channels to carry away the purified gas from the purifier, common inlet and outlet chambers from which said channels branch, means for controlling the inlet openings, girders for supporting said louvers, adjustable rods mounted vertically in the purifier, and pivotal connections between the louvers and said adjustable rods.
10. In a gas purifying device the combination of gas channels formed by roof-like louvers arranged one above the other for introducing the gas to be purified into the purifier, similar louvers for carrying away the purified gas from the purifier, throttle valves arranged in the inlet openings, means for controlling the passage of gas, girders for supporting said louvers, adjustable rods mounted vertically in the purifier, and pivotal connections between the louvers and said adjustable rods.
11. In a gas purifying device the combination of gas channels formed by roof-like louvers arranged one above the other for introducing the gas to be purified into the purifying mass, similar louvers for carrying away the purified gas from the purifier, means for controlling the inlet openings, girders for supporting said louvers, adjustable rods mounted vertically in the purifier, pivotal connections between the louvers and said adjustable rods, outlet hoppers in the bottom of the purifier, and means for maintaining such outlet hoppers closed.
12. In a gas purifying device the combination of gas channels formed by roof-like louvers arranged one above the other for introducing the gas to be purified into the purifying mass, similar louvers for carrying away the purified gas from the purifier, said channels being distributed throughout the whole of the purifying mass, alternating in vertical rows with each other and branching off from common inlet and outlet chambers.

bers, with means for controlling the inlet openings comprising a differential pressure gage device operated by the pressure in front of and behind the throttle valve, girders for supporting the louvers forming said channels, adjustable rods mounted vertically in the purifier, pivotal connections between the louvers and said adjustable rods, outlet hoppers in the bottom of the purifier, and

means for maintaining such outlet hoppers closed.

In testimony whereof I have signed this specification in the presence of two subscribing witnesses.

CARL WEGESCHEIDT.
